TEXTILE FABRIC

Connie C. Willoughby, New York, N.Y., assignor to Cannon Mills Company, Kannapolis, N.C., a corporation of North Carolina

Filed Jan. 28, 1970, Ser. No. 21,119

Term of patent 14 years

Int. Cl. D5—02

U.S. Cl. D92—1

FIG. 2

FIG. 1 is a top plan view of a textile fabric showing my new design with a repeat of the design being enclosed within the dotted lines; and

FIG. 2 is an enlarged top plan view of one repeat of the design and corresponding substantially to that area enclosed within the dotted lines of FIG. 1.

I claim:

The ornamental design of a textile fabric, substantially as shown and described.
